US00D442474S

(12) **United States Design Patent** (10) Patent No.: **US D442,474 S**
 Piccioli et al. (45) Date of Patent: ** May 22, 2001

(54) **BOTTLE**

(75) Inventors: **David P. Piccioli**, Auburn; **Suppayan M. Krishnakumar**, Nashua; **Wayne N. Collette**, Merrimack, all of NH (US); **John Bretz**, Crystal Lake, IL (US)

(73) Assignee: **Stokely-Van Camp, Inc.**, Chicago, IL (US)

(**) Term: **14 Years**

(21) Appl. No.: **29/102,535**

(22) Filed: **Mar. 26, 1999**

(51) LOC (7) Cl. **09-01**

(52) U.S. Cl. **D9/307**; D9/539

(58) Field of Search D9/307, 538-540, D9/553, 539; 215/381-384, 400

(57) **CLAIM**

The ornamental design for a bottle, as shown and described.

DESCRIPTION

FIG. 1 is a perspective view of a bottle showing a new design;

FIG. 2 is a front elevational view of the bottle depicted in FIG. 1, the opposite rear elevational view being identical;

FIG. 3 is a side elevational view of the bottle depicted in FIG. 2, representing a partial rotation of the bottle about its vertical center axis from the front elevational view depicted in FIG. 2, the opposite side elevational view being identical; FIG. 4 is a top plan view the bottle depicted in FIG. 2; and,

FIG. 5 is a bottom plan view of the bottle depicted FIG. 2. The broken line environmental showing is for illustrative purposes only and does not form part of the claimed design.
